UNITED STATES PATENT OFFICE.

RALPH B. HAIN, OF GRAND RAPIDS, MICHIGAN.

DESIGN FOR AN ENGINE-CASING.

SPECIFICATION forming part of Design No. 24,318, dated May 14, 1895.

Application filed January 21, 1895. Serial No. 535,738. Term of patent 14 years.

To all whom it may concern:

Be it known that I, RALPH B. HAIN, a citizen of the United States, residing at Grand Rapids, in the county of Kent and State of Michigan, have invented a certain new and original Design for a Casing for Engines; and I do hereby declare the following to be a full, clear, and exact description of the invention, such as will enable others skilled in the art to which it appertains to make and use the same.

This design relates to a design for the casing for an engine, and the distinctive features consist in a cylindrical body B arranged with its axis horizontal; a principal cylindrical body D above the body B, with its axis arranged vertically and being also connected to the body B by a reduced cylindrical neck C; and an upwardly extending cylindrical extension E above the principal cylindrical body D, as more fully illustrated in the accompanying drawings, in which—

Figure 1 is a side elevation of a casing, showing said design; and Fig. 2 an elevation of the same at right angles to that of Fig. 1.

Like letters refer to like parts in both of the figures.

A represents a horizontal bed plate, imme-

diate above which is a short cylindrical body B, with its axis arranged horizontally. B', B' are discous plates having cylindrical 30 oppositely projecting central portions B''. At the middle of said body B is an outwardly projecting circumferential rib B''' abutting against the respective sides of an upwardly extending cylindrical neck C connecting the 35 body B with the base of the main cylindrical body D, the latter having its axis arranged vertically.

Above the body D and with its axis in line with the axis of the same and extending upward therefrom is a reduced cylindrical body E terminated at the top by an outwardly projecting band or cap, having a concave lower side and a convex upper side, all substantially as shown.

What I claim is—

The design for an engine casing, substantially as shown and described.

In testimony whereof I affix my signature in presence of two witnesses.

RALPH B. HAIN.

Witnesses:

LUTHER V. MOULTON,
LEWIS E. FLANDERS.
